UNITED STATES PATENT OFFICE.

WILLIAM H. WIGMORE, OF PHILADELPHIA, PENNSYLVANIA.

APPARATUS FOR DISTRIBUTING GASES.

SPECIFICATION forming part of Letters Patent No. 718,941, dated January 20, 1903.

Application filed July 30, 1902. Serial No. 117,630. (No model.)

To all whom it may concern:

Be it known that I, WILLIAM H. WIGMORE, a citizen of the United States, and a resident of the city and county of Philadelphia, State 5 of Pennsylvania, have invented certain new and useful Improvements in Apparatus for Distributing Gases, of which the following is a specification.

My invention relates to improvements in 10 apparatus for disinfecting; and the object of my invention is to furnish an apparatus for the safe carriage and distribution of formic acid or other gases, as will be hereinafter fully described.

15 In the accompanying drawings, forming part of this specification, Figure 1 is a central sectional elevation of my gas-carrying cylinder in place in the distributing-cylinder, and Fig. 2 side elevations and a plan of the needle 20 for puncturing the gas-carrying cylinder.

a is the gas-carrying cylinder, which is made of thin metal and which is charged with the gas to be used. In practice I usually charge the cylinder *a* with a pressure of about twenty

25 pounds to the square inch of gas. The sides of the top *b* of the cylinder *a* are preferably pinched together, as shown, and soldered to form a seal to retain the gas.

The cylinder *a* is placed in a distributing- 30 cylinder *c*, which is furnished at its top with an opening *d*, through which the gas-carrying cylinder may be inserted or withdrawn, which can be tightly closed by a screw-plug *e*.

f is a step with flaring sides carried by the 35 bottom *g* of the cylinder *c*, which holds the lower end of gas-cylinder *a*.

h is a guide-ring, through which the cylinder *c* is passed.

The step *f* is made with flaring sides, as 40 shown, so that the lower end of the cylinder may be thereby guided to its seat, and this step and the ring *h*, which engages the cylinder near its top, hold the cylinder *a* in place within the cylinder *c*.

45 *i* is a threaded spindle carried by a threaded bearing *j*, carried by the cylinder *c*.

k is a gland to prevent leakage past the spindle *i*, and *l* is a hand-wheel upon the spindle, by means of which this latter may be 50 turned.

The point *m* of the spindle is oval in section, as best shown in Fig. 2, and when the

spindle is revolved and driven through the side of cylinder *a* it reams out a hole of circular section, and as the section of the point 55 is oval or elliptical the gas can pass out the circular hole formed by the turning of the point without first withdrawing the spindle from it.

As soon as the cylinder *a* is punctured the 60 gas therein contained passes to the interior of cylinder *c*, which carries a tube *n*, closed at the bottom and furnished with small perforations *o* on its sides, which is connected with or terminates in a tube *p*, which passes 65 out of the cylinder *c* and which is adapted to be connected with a hose which leads the gas to the point where it is to be applied.

The purpose of the perforations *o* in pipe *n* is to cause a substantially uniform mixture 70 of air and gas to pass to the outlet of this pipe from the cylinder *c*, these perforations admitting to the pipe *n* air and gas simultaneously from the upper and lower parts of the cylinder and from several points intermediate of 75 the top and bottom.

r is a needle-valve by means of which the flow of gas to the tube *p* may be controlled.

s is a pressure-gage for indicating the pressure within cylinder *a*. This gage consists 80 of a glass tube *t* outside cylinder *a*, closed at the top and forming part of or connected at the bottom with a tube *u* within cylinder *c*. At the upper end tube *u* is enlarged or is connected with a tube *v* of greater diameter. 85

w is a funnel-like tube, the upper part of which engages the inner upper part of the tube *v*, as shown, and the lower part of which extends down in this tube.

The upper part of the tube *t* contains air, 90 and the lower part of this tube and the lower part of tube *u* contain mercury, while the upper part of tube *u* is open to the interior of cylinder *c*. The tube *t* is properly graduated, and the height of the mercury therein indicates the pressure of gas within cylinder *a*. 95

The tubes *v* and *w* are arranged as shown and described in order that the mercury may not be spilled if the cylinder *c* fall upon its side.

100 The cylinders *a* are small and light and can readily be shipped long distances, and they are preferably made of such a size that they will contain sufficient gas for several

treatments if the gas be used for medical purposes after their contents have been transferred to the cylinder.

Having thus described my invention, I claim as new and desire to secure by Letters Patent—

1. In an apparatus for distributing gas under pressure, in combination, a distributing-cylinder furnished with an opening for introducing a gas-carrying vessel, means for tightly closing the opening in said cylinder, means for puncturing said gas-cylinder while within said distributing-cylinder, and a valve-controlled pipe whereby said gas may be withdrawn from said distributing-cylinder.

2. In a gas-distributing apparatus, in combination, a distributing-cylinder furnished at one end with an opening for the introduction of a gas-carrying vessel, means for tightly closing said opening, a step with flaring sides at the bottom of said distributing-cylinder, a guide near the upper end of said cylinder, means for puncturing said gas-cylinder, and

a valve-controlled means for withdrawing the gas from said distributing-cylinder.

3. In a gas-distributing apparatus, in combination, a gas-carrying vessel, a distributing-cylinder in which said gas-carrying vessel is placed, means for sealing said distributing-cylinder, means for puncturing said gas-carrying vessel while within said distributing-cylinder, a valve-controlled tube for withdrawing gas from said distributing-cylinder, and a pressure-gage for indicating the pressure within said distributing-cylinder.

4. The combination with the distributing-cylinder and the gas-carrying vessel, of a threaded bearing carried by the former, a threaded spindle with a point of oval cross-section, and means whereby said spindle may be turned.

WILLIAM H. WIGMORE.
